Attorney.

UNITED STATES PATENT OFFICE.

TADEUSZ ZDRODOWSKI, OF PITTSTON, PENNSYLVANIA.

FILE SHEATH.

Application filed November 23, 1922. Serial No. 602,908.

To all whom it may concern:

Be it known that I, TADEUSZ ZDRODOWSKI, a citizen of Poland, residing at Pittston, in the county of Luzerne and State of Pennsylvania, have invented certain new and useful Improvements in File Sheaths, of which the following is a specification.

This invention relates to certain new and useful improvements in file sheaths and has particular reference to a casing of elongated form for housing the blade of a file to protect the file sheath during shipment.

The primary object of the invention is to provide a sheath for files wherein the sheath casing is provided with a fabric lining with a hinged section carried by the casing to facilitate positioning of the lining therein.

With the above and other objects in view as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a perspective view of a file sheath constructed in accordance with the present invention, the file being shown in position therein,

Figure 2 is a cross sectional view taken on line II-II of Fig. 1 showing the hinged section of the sheathing,

Figure 3 is a fragmentary top plan view, Figure 4 is a fragmentary perspective view of the open end of the sheath with the hinged section moved to open position,

Figure 5 is a perspective view of the open end of a modified form of sheath showing the fabric lining retained by the beaded edges of the sheath casing,

Figure 6 is a fragmentary perspective view of the closed end of the sheath, and

Figure 7 is a detail sectional view of the form of the invention shown in Figs. 5 and 6 illustrating the inwardly directed bead carried by the sheath for frictionally engaging the faces of the file blade.

Referring more in detail to the accompanying drawing, and particularly to Figs. 1 to 4, there is illustrated a file sheath em-

bodying a casing having a bottom wall 1, integral end walls 2 and 3 and an integral upper wall section 4, the sheath being preferably constructed of sheet metal and bent into the cross-sectional formation shown in Fig. 2, one end being closed and the other end open as shown in Figs. 1 and 4 for the reception of the file F.

The upper wall section 5 has one edge 60 thereof flanged to provide an end wall section 3^a adjacent the lower end wall 3, said end wall sections 3 and 3^a being longitudinally hinged as at 6 and clearly shown in Figs. 2 and 3. The connection between the adjacent edges of the upper wall sections 4 and 5 includes struck-out spring fingers 7 carried by the free edge of the wall section 4 that are adapted to be received in openings 8 formed in the adjacent free edge of 70 the upper wall section 5, the spring fingers 7 resiliently retaining the hinged cover section 5 in the closed position shown in Fig. 2.

A fabric lining 9 is provided for the sheath, one edge thereof being engaged by 75 spurs 10 carried by the free edge of the cover section 4 and completely covering the inner face of the sheath, the hinged cover section 5 being primarily provided to permit the proper positioning of the lining 9 80 within the sheath, while the file F is positioned therein by being slid through the open end thereof.

In the form of the invention shown in Figs. 5 to 7, the sheath is constructed of a single sheet of material bent into the desired shape with the meeting edges of the upper wall sections 4^a and 5^a formed into a bead 11 to be so retained, the indentures 12 in the bead forming a substantial locking connection between the adjacent edges. The fabric lining 9^a covers the inner face of the sheath and has the edges thereof secured in the bead 11. To prevent accidental displacement of the file F from the sheath, the side and end walls thereof adjacent the open end, as shown in Fig. 5, are provided with an inwardly pressed rib 13 that frictionally engages the file F for the purpose intended.

While there are herein shown and described the preferred embodiments of the present invention, it is nevertheless to be

understood that minor changes may be made therein without departing from the spirit and scope of the invention as claimed.

What is claimed as new is:—

5 In a file sheath, an elongated sheath casing having one open and one closed end, said casing being formed of a sheet of metal secured together at the longitudinal meeting edges by a bead, a fabric lining for the cas-

ing secured at the meeting edges by said 10 bead, said bead having depressions formed therein for locking said edges, and an inwardly pressed rib formed in the walls of the casing adjacent the open end for frictional engagement with a file. 15

In testimony whereof I affix my signature.

TADEUSZ ZDRODOWSKI.
